United States Patent Office

Des. 183,527
Patented Sept. 16, 1958

183,527

ORNAMENT FOR AN AUTOMOBILE FENDER

Jack E. Kenitz, Detroit, Mich., assignor to Chrysler Corporation, Highland Park, Mich., a corporation of Delaware

Application August 5, 1957, Serial No. 47,212

Term of patent 7 years

(Cl. D14—18)

Fig. 1 is a side elevational view of an ornament for an automobile fender, showing my design;

Fig. 2 is a top plan view thereof;

Fig. 3 is a front elevational view thereof; and

Figs. 4 and 5 are sectional views taken on the lines 4—4 and 5—5 of Fig. 2.

I claim:

The ornamental design for an ornament for an automobile fender, substantially as shown.
